UNITED STATES PATENT OFFICE.

JOHN W. OSBORNE, OF WASHINGTON, DISTRICT OF COLUMBIA, ASSIGNOR
TO WILLIAM H. FORBES, OF BOSTON, MASSACHUSETTS.

LITHOGRAPHIC PRINTING.

SPECIFICATION forming part of Letters Patent No. 391,065, dated October 16, 1888.

Application filed May 2, 1881. Serial No. 32,287. (No model.)

To all whom it may concern:

Be it known that I, JOHN W. OSBORNE, of Washington, District of Columbia, have invented a new and useful Improvement in 5 Lithographic Printing, of which the following is a specification.

My invention relates to the printing of all surfaces from which impressions are taken in the lithographic manner—that is, by first 10 damping said surface, then inking it, and, lastly, printing from it on paper, &c., by the application of pressure, and it has special reference to the first in this series of operations.

Hitherto the damping of lithographic stones 15 and similar surfaces, as zinc and photo-collographic plates, has been effected by a sponge, cloth, or by rollers. The latter are universally used in lithographic power-presses at the present time, and in the following description I 20 shall explain my method as it may be applied to the damping of a stone adjusted for printing in such a press.

The principle upon which my invention is based may be thus stated. When air saturated 25 with water in the form of elastic vapor is brought in contact with a colder substance, a part of the water so contained will be deposited on the surface of the colder body in the liquid form, as dew. This takes place be- 30 cause any lowering of the temperature of air which is saturated lessens its capacity for watery vapor and results in the precipitation of the difference between the quantities it can take up at the two temperatures. When the 35 air is not saturated, moisture will still be de- posited if the temperature of the colder body be at or below the "dew-point"—that is, cold enough to reduce the stratum of air in contact with it to a temperature just below 40 that at which the amount of water present is sufficient for saturation. The first case is well illustrated by the film of condensed moisture produced when we breathe upon a plate of glass or of polished metal, which is colder than 45 the saturated air issuing from the lungs; the second by the condensation of water as dew upon the glass and other objects out of doors when the same have been cooled to the dew-point by radiation. The well-known appear- 50 ance of moisture upon the outside of a vessel

of ice-water when placed in a warm room is also a case of deposition from partly-saturated air.

To apply this principle to the damping of lithographic stones and similar surfaces, I carry 55 to such a surface an atmosphere of air charged with vapor of water to the point of saturation or near it at a temperature above that of the stone to be damped. As a consequence the relatively cold surface becomes instantly covered 60 with a film of condensed moisture. The amount of this deposit is influenced by the temperature at which the saturation was effected, by the difference between that and the tempera- 65 ture of the stone or other surface, the capacity of the latter as a conductor of heat, and the volume of saturated air blown over the same.

In the drawings forming part of this specification, Figure 1 shows in plan part of a lithographic power-press with a stone upon the 70 reciprocating bed and the damping apparatus taking the position usually occupied by the damping-rollers. Fig. 2 is an elevation of the apparatus, looking toward the impression-cyl- 75 inder, with parts of the press and the stone in section. Fig. 3 is an elevation of the apparatus as seen from the side of the press. Fig. 4 is a section through the saturating-box on a vertical plane passing through the ingress and egress openings and showing the perforated 80 termination of the steam-pipe, &c. Fig. 5 is an elevation of part of the exit-tube conveying the saturated air, showing its relation to the press-framing and stone, on double the scale of the preceding figures. Fig. 6 is an elevation 85 of part of the exit-tube for compressed air, showing its relation to the press-framing and stone, on same scale. Fig. 7 is a cross-section of both the foregoing exit-tubes on line $x-x$, Figs. 1 and 2, showing also the screen between 90 them, on same scale. Fig. 8 shows in section the relative position of the several parts of the damping apparatus in a lithographic power- 95 press when double damping is used, small scale. Fig. 9 shows in longitudinal section the way in which an induced current of air may be established by the force of the jet of steam used to saturate it. Fig. 10 shows an end elevation of thin elastic pieces of different size for attachment to the saturated air-exit 100

tube, on the large scale. Fig. 11 shows a plan view of three such pieces, same scale.

The tube *a* leads from a fan-blower or similar source of air at low pressure. It enters the closed saturating-box *b*, the escape from which is by the upright tube *c* to the exit-tube *d*, which crosses the stone or other printing-surface as it reciprocates beneath it. The supply of air to the saturating-box is controlled by the valve *e*, and the discharges of saturated air upon the stone are determined by the cock *f*, worked automatically by a cam or other suitable device moving with the press, which opens and closes it at proper times. The quantity of saturated air which passes through the tube *c* every time *f* is opened is further controlled by the cock *g*. With this cock the workman brings the quantity of water furnished to the printing-surface down to a minimum while the press is running without disturbing any of the other adjustments.

The saturation of the air with water-vapor is effected by the admission of steam at low pressure through the tube *h*, the intervals of admission being determined by automatic movements of the cock *i*, corresponding in time to those of *f*, while the gross quantity which can pass through the tube *h* is governed by the cock *k*. The steam issuing in fine jets from the perforated sides of the pipe *h*, Fig. 4, meets the incoming current of air, raises the temperature of the same in proportion to its quantity, and passes as vapor at that temperature into the air, which thereby becomes saturated. These changes take place with great rapidity, and they are still further promoted if the air and steam be thoroughly mixed. The circumstances under which the two gasiform bodies enter the saturating-box are favorable to this mixing, and the partitions in the box *b*, as shown in Fig. 4, render it still more perfect. The box *b* and tube *c* should be covered with felt or other non-conducting material, (which is omitted in the drawings,) to prevent changes in their temperature due to external causes, and the whole apparatus should be blown through to warm it before it is used. This is effected by opening the cock *l* in the tube *m*, which leads to some waste-pipe, and all the other cocks except *f*. The relative quantities of air and steam are then so adjusted by *e* and *k* that the mercury in the thermometer *n*, the bulb of which is in the tube *c*, rises to the temperature fixed upon and remains there stationary. *l* and *i* are then closed, and the apparatus is ready for work.

Whenever in the automatic damping of the printing-surface the cocks *f* and *i* are opened, the air passing through *c* will have the constant temperature determined on, and will be practically saturated at that temperature as long as the air and steam are supplied at constant pressures.

The tube *c* leads from the saturating-box to some convenient place, where it is closed by a water seal sufficient to counterbalance the pressure of the incoming air through the tube

a. Its function is to remove any water blown into *b*, or which may be condensed therein, the quantity of which will always be small.

The saturating-box, with its connections, is herein shown and described as in close proximity to the press; but this is by no means a necessary arrangement, for it may be placed at a considerable distance with equally good results, and often with advantage, if the tube *c*, bringing the saturated air, be well covered, so as to prevent it cooling, and thereby condensing the water-vapor before it reaches the stone. The tube *d*, at right angles to *c*, crosses the press above the stone and is closed at its farther end. On its under side, for the whole width of the stone, it is pierced with holes, through which the saturated air from *c* finds ready egress. This tube is made of some non-conducting material—such as hard rubber—and over the perforated part a fold of similar material descends on both sides to within a short distance of the stone. The two ends of this dependent chamber are closed, and the whole “exit-tube” so constructed (which the drawings will make intelligible) is attached to the tube *c* by the coupling *p*, and is also stiffened and supported by a rigid metallic bar, which is bolted at each end to the press-frame at *q*. The small recessed grooves on the outside of this exit-tube along the part nearest to the stone are for the reception of the turned-up edges of the thin pieces *r r r*. (See Figs. 10 and 11.) Several of these pieces, made of very thin hard rubber, are provided of different widths. They are used, as required, to shorten the length of the open part of the exit-tube to suit the varying sizes of stones, and also (by employing those which are narrow) to modify locally on the stone the amount of precipitated moisture, decreasing it roughly in proportion as the printing-surface is covered by work. This they do by intercepting to some extent the downward flow of saturated air, which, nevertheless, finds its way round and under them, so as still to damp the stone, but in a lesser degree. These pieces are attached to the exit-tube when wanted simply by clasping them upon it and then sliding them into position, which position they then hold by virtue of their elasticity.

When one edge of the stone reaches the exit-tube *d*, the cocks *f* and *i* are thrown open, and they are closed again when the other edge leaves said tube. During this interval the saturated air (say at a temperature of 120° Fahrenheit) has been blowing down upon the cold surface, upon which a beautifully regular and perfect film of water is condensed. This disposition of dew is instantaneous and inevitable, because the least lowering of the temperature of the saturated air causes a separation of the water, which, in consequence of the cooling it is subjected to at the printing-surface, it can no longer contain. This takes place upon every part of the surface reached by the current of air, so that all the edges, as well as the face of the stone, become damped.

It is not difficult to distribute the air very uniformly, and therefore the damping is uniform; but (due to their slightly-better conducting-power) the bare parts of the stone will 5 receive more water than those places which are protected with ink, the repulsive power of the latter also tending to bring about the same result.

I believe myself to be the first to provide a 10 method and means adapted for automatically delivering to those portions of the stone which bear no image a greater amount of water than to those portions which bear the image. The advantages, which are very great, lie, principally, 15 in the fact that I am enabled in this manner to effectually dampen the stone, so as to prevent it from taking ink at points outside of the image without depositing upon the portions which bear the ink so much water as to 20 impair the quality of the ink. In the ordinary system of damping great difficulty is encountered in consequence of the water becoming mechanically incorporated with the ink.

The quantity of water deposited will be influenced 25 by the temperature at which the saturation is made, the coldness of the printing-surface as compared to that temperature, and the volume of air blown over it during its transit under the exit-tube *d*. The first and last of 30 these conditions, it will be seen, are completely under control; but the phenomena accompanying the precipitation of moisture are adverse for the maintenance of a wide difference in 35 temperature between the printing surface and the saturated air. This arises from the fact that it is impossible for that surface to cool the air and condense the water required to damp it without becoming warmer in consequence. The accession of heat, however, will 40 be found to be very slight, because the damping by this method is so perfect that an exceedingly small amount of water is sufficient. In cool weather it will cause no difficulty for a moment after each slight accession of heat is 45 received. The inking-rollers from a cold inking-table, with their heavy riders, act as most efficient cooling agents, as does also the cold sheet of paper on the impression-cylinder, which in the act of printing is pressed into intimate contact 50 with the whole surface of the stone. In other words, the little increments of heat imparted to the stone have not only to warm it cumulatively to an inconvenient temperature, but also to warm the inking-rollers, their 55 riders, the ink-table, and all the paper printed while the press is running. The warming of the stone due to the condensation of the water required for damping would, if considerable, prove inconvenient; but even then, as long as 60 a difference in temperature is made to exist between the stone and the saturated air flowing over it, a deposition of water will take place.

In warm weather, when the printing-surface 65 and all parts of the press have acquired the temperature of the air, it is expedient to cool the former, or at least to prevent an increase

of its heat. This may be accomplished in a variety of ways; but I prefer to use for that purpose air which has been compressed by 70 mechanical means and cooled. The tube *s* leads from a receptacle into which air has been pumped until a considerable pressure—say fifty or sixty pounds to the square inch—has been reached. The heat evolved by this 75 compression must be absorbed by a circulation of cold water, the evaporation of ammonia, or in other ways until the air in the receiver reaches the lowest temperature easily available, which is commonly that of the hydrant water on the premises. The details of this operation are well understood and need not be more fully described. The tube *s* leads to the exit-tube *t*, which crosses the press. The cock *u* controls the volume of air which 80 can pass through the tube *s*, and with it the workman regulates the degree to which he cools the stone while the press is running, and the cock *v* is opened and closed automatically by the press at the times when the exit 85 tube *t* is required. The exit-tube *t* is made of some non-conducting substance, such as hard rubber, which answers the purpose very well. It is attached to *s* by a coupling, and is closed at the farther end. 90 All along its lowest part the tube *t* is pierced by a close row of small holes, from which the compressed air issues downward upon the stone. This exit-tube is further stiffened and strengthened by a metallic bar, as in the case 95 of the exit-tube for saturated air, which is bolted in like manner to the press framing on each side. The position of this tube is parallel to that from which the saturated air flows and at a short distance behind it—that is, farther from the impression cylinder. The air issues from this tube very near the stone. At the moment of its escape it expands suddenly, and in doing so absorbs an immense quantity 100 of heat, a large part of which it takes from the surface of the stone, which is cooled in consequence and its temperature kept at any desirable number of degrees below that of the saturated air, notwithstanding the heat due to the condensation of vapor which takes place 105 upon it.

The cooling may take place while the stone is moving in both directions. The saturated air for damping I find it best to apply only when the stone is moving toward the inking-rollers, and the cams which move the cocks *v* and *u* are constructed and adjusted accordingly.

To prevent disturbance of the saturated air by the current of air under high pressure issuing from the tube *t*, it is well to interpose 125 the shield or screw *w*, which is also made of non-conducting material. It is placed perpendicularly between the two exit-tubes, and its lower edge is as near the stone as may be. Its position should be such as not to interfere 130 with the expansion of the air from *t*.

The employment of non-conducting material for the construction of the two exit-tubes is recommended; but, though advantageous, its

use is not imperative, and many substances can be used as well as hard rubber. The object aimed at is in the one case to hinder a cooling of the saturated air and in the other to hinder a warming of the expanding air before either current reaches the stone. A non-conducting substance is likewise recommended for the screen *w*, to prevent the expanded air from *t* lowering its temperature on the side exposed to the excess of saturated air issuing from under the exit-tube *d*, and the consequent deposition of water thereupon.

With this damping apparatus as described it is possible to print with an exceedingly small quantity of water, (a great desideratum in lithographic printing;) but the quantity may be still further reduced by placing an exit-tube for saturated air on the other side of the impression cylinder beyond the inking-rollers. The relative position of the two exit-tubes is shown in Fig. 8. This can be done because of the very small space required for the damping apparatus. It is not then necessary to supply water in the first instance sufficient for a double rolling in with ink, for considerably less than half the usual quantity required applied from each exit-tube will be found sufficient.

In a reciprocating lithographic press a single damping apparatus placed behind the impression-cylinder, as is commonly done, damps the stone as it travels forward. When this is accomplished, the stone passes first under the impression-cylinder without touching it, and then under the inking-rollers, which successively traverse its surface. After this the bed of the press has its direction of movement reversed, and the lithographic stone or surface with the design upon it returns. It passes first under the inking-rollers, then under the impression-cylinder bearing the sheet to be printed, the cylinder being urged downward, and finally to the damping apparatus, when all the foregoing operations are repeated. It will be seen that in such a press the quantity of water applied to the stone must be sufficient to keep its non-printing portion from taking ink while the stone is going forward under the inking-rollers, as well as during its return thereunder.

Recurring now to my method of damping, (shown in Fig. 8,) in which the total quantity of water is divided into two portions applied at different times, the following sequence of events is observed: As the stone in its forward movement passes under the exit-tube placed behind the impression-cylinder, the saturated air is caused to flow out upon it in such quantity as to produce a film of moisture sufficient to protect it during its passage under the inking-rollers in one direction only. Under these circumstances were the motion of the bed to be reversed the surface being dried would take ink all over. This is prevented by letting the saturated air flow from the second exit-tube, placed in front of the rolls, as soon as the stone begins its backward move-

ment thereunder. In this way it will be perceived that the stone is damped preparatory to passing back under the inking-rolls to the impression-cylinder with a film of water just sufficient to protect it during that short interval. In the ordinary system of inking all the water is applied at once for the complete inking, the quantity being far greater than that required for the first roll, so that it tends to impair the excellence of the ink, with which it becomes incorporated to a greater or less extent. In my system I precipitate only enough water for each rolling upon the stone before the rollers act thereon, in consequence of which the inking is done with a minimum amount of water—a result highly advantageous in practice, in that it permits a clean impression and prevents the deterioration of the ink. In the old system the inking-rollers nearest the impression-cylinder receive the most water, and, being the last to leave the stone before the impression is made, they "load the work up," as it is technically termed, with the ink at the finish, whereas in my system the terminal rollers are brought in contact with equal amounts of water, and the rollers which leave the stone last carry ink which has been damped by much less than half the total quantity of water.

Recurring to the method herein described for saturating the air with water-vapor, it should be stated that I am well aware there are many other ways in which a like result can be accomplished. It is, for instance, quite possible to use as a motive force for the saturated current the same jet of steam which supplies the moisture, for such a jet of steam discharged under pressure and blown into an open tube will draw a large quantity of air after it in the way shown in Fig. 9, which will be readily understood without further description; but in view of the several conditions to be fulfilled—namely, temperature, force, and approximate saturation, and the wide range of each required to suit varying circumstances—I believe the method described to be the simplest and best, demanding, as it does, very little in the way of nice adjustment on the part of the workman. Likewise, I believe the construction and manner of applying the exit-tubes to be the best for the ends in view; but I do not confine myself to those forms and to that arrangement, as it is obvious that both may be modified without affecting the character of my invention or the principles involved. Furthermore, I am aware that the method herein described for cooling the stone or preventing its temperature rising in consequence of the condensation of water determined by it is not the only way in which that end may be accomplished. It is possible, for instance, to use for that purpose a current of air which has passed over ice, or over a mixture of ice and salt, &c., or to cool the stone by radiation to an artificially-cooled body in close proximity to it when it runs behind the impression-cylinder, or two such bodies may be

used, one before and one behind the impression-cylinder, or to cool the ink-table artificially, and so cool the stone indirectly, as well as in other ways; but I believe that the method 5 herein set forth, though I do not confine myself to it, is the most convenient and economical, and I have accordingly fully described it. It should also be stated that while from an abstractly theoretical point of view the 10 principles of my invention admit of perfect application under widely-varying conditions of temperature, the degree to which the stone must be cooled or the air warmed to secure sufficient and satisfactory damping is by no 15 means a matter of indifference to the practical printer. If, for instance, the lithographic stone were by the means described cooled down to some temperature near the freezing-point, its surface would become coated with 20 dew from the atmosphere, as it exists in most workshops, under which circumstances sufficient damping could undoubtedly be accomplished by blowing the ordinary air over the stone in sufficient quantity, obviating, apparently, the necessity for special apparatus to 25 saturate it with the vapor of water; or, to take the other extreme, the temperature of the stone might be allowed to rise very high indeed, and still precipitate water if the temperature of saturation were correspondingly raised; but in either of these cases the printing qualities of the stone would probably be affected, and difficulties might arise which do 30 not exist at present.

35 As far as the increase of temperature due to condensation is concerned, it may also be said that it remains the same for the same quantity of water restored to the liquid form whether the saturation be made at a low or high temperature. It is quite possible, for example, to damp the stone very effectively with steam at 40 212°. This would be an extreme case, one in which the proportion of air had finally vanished, and though a serviceable method under 45 certain circumstances and in certain forms of press, and quite in accord with the principles of my invention, still it gives rise to difficulties, all of which need not be discussed in this specification. It may, however, be well to explain in reference to it that while the absorption 50 of heat necessary to condense the water required for damping is no greater than if the same were condensed from saturated air at 100° the temperature of the constant quantity 55 of water so precipitated is in each case the same as that of the medium from which it is derived, (212° and 100° in the supposed cases.) To cool this water, however small it may be, adds another increment of heat to the 60 stone, which leads to the general conclusion that the lower the temperature at which the saturation is effected the less will be the increase of temperature of the stone after each damping. If, on the other hand, the saturating 65 temperature be too low, an inconveniently large volume of air will be required. In my experience temperatures varying from 110° to

130°, according to circumstances, have proved most generally serviceable.

Under the term "saturated air" as used in 70 this specification and in the claims I include not only air which has taken up the largest possible amount of water in the form of elastic vapor, but also air which has approximately attained that condition, and generally 75 air so charged with watery vapor at a temperature above that of the surface to be damped that in contact with such a surface it practically accomplishes the end in view, even though in a strictly scientific sense it be imperfectly 80 saturated. This explanation is desirable, because it may often prove convenient and economical in practice to employ imperfectly-saturated air and make up for deficiency in that respect by increasing the volume of such air 85 conveyed to the printing-surface until the requisite quantity of water is obtained at each damping; and in this specification and in the claims, when reference is made to an atmosphere which "contains the vapor of water," 90 I wish it to be understood that such an atmosphere may according to its temperature consist of such vapor in any proportion, increasing relatively to the air present from the small amount existing in the air we breathe (from 95 which moisture will abundantly be precipitated if the printing-surface is sufficiently cooled) to that in which, the temperature having reached 212°, the vapor of water or "steam," 100 as it would then be called, becomes the sole atmosphere present to the exclusion of air, for the condensation of such steam upon a cold surface, giving rise to a film of dew, is governed by laws precisely the same as those which determine the precipitation of a similar film from 105 saturated air at any temperature. In the latter case the air present plays no part as far as the quantity of available water is concerned or the temperature at which condensation takes place and may be totally disregarded, the water-vapor filling the space occupied by the air exactly as if no air were present.

The advantages of the method I have invented for damping surfaces prepared for printing in the lithographic manner will be 115 obvious to all persons conversant with the art. As compared with the usual damping method, it may be said that it obviates all the trouble and delay due to the management of the water-fountain and the preservation of the rollers in 120 an efficient condition. It damps the edges of the stone as well as the face. It can be applied both before and behind the impression-cylinder. The water used comes into existence as water of great purity only on the printing-surface, the distribution and quantity of which are thoroughly under control, and the tendency of which is to accumulate on the places where there is no work. Finally, the water is applied without the contact of any 125 solid body.

By the expressions "surface" and "printing-surface" as herein employed is meant a stone, metal, or equivalent body having its

face adapted for printing in the lithographic manner, this being the sense in which the term "surface" is commonly used in the art of lithographic printing.

5. Having thus described my invention, what I claim, and wish to secure by Letters Patent, is—

1. The improvement in the art of printing in the lithographic manner, which consists in first exposing the printing-surface to an atmosphere containing the vapor of water, the dew-point temperature of which is higher than the temperature of said surface, and from which said surface obtains water by condensation, then inking the printing-surface so damped, and finally printing from the same on paper or other flexible material, substantially as and for the purpose described.

2. The improvement in the art of printing in the lithographic manner, which consists in first cooling the printing-surface, then exposing it to an atmosphere containing the vapor of water, the dew-point temperature of which is higher than the temperature to which said surface has been cooled, and from which it obtains water by condensation, then inking the printing-surface so damped, and finally printing from the same on paper or other flexible material, substantially as and for the purpose described.

3. The improvement in the art of printing in the lithographic manner, which consists in first exposing the printing-surface to the cooling effects of expanding air, then to an atmosphere containing the vapor of water, the dew-point temperature of which is higher than the temperature to which said surface has been cooled, and from which it obtains water by condensation, then inking the printing-surface so damped, and finally printing from the same on paper or other flexible material, substantially as and for the purpose described.

4. The improvement in the art of damping surfaces prepared for printing in the lithographic manner, which consists in first cooling

the surface to be damped and then discharging upon it an atmosphere of the vapor of water or of air saturated with the vapor of water at a temperature above that to which said surface has been cooled, substantially as and for the purpose described.

5. The improvement in the art of damping surfaces prepared for printing in the lithographic manner, which consists in first cooling the surface to be damped by the sudden expansion of air (which has been mechanically compressed and cooled) in contact with said surface, and then discharging upon the same an atmosphere of the vapor of water or of air saturated with the vapor of water at a temperature above that to which said surface has been cooled, substantially as and for the purpose described.

6. The improvement in the art of damping surfaces prepared for printing in the lithographic manner, which consists in locally adjusting the supply of water to the requirements of different parts of said printing-surface by interposing one or more obstructions, as *r*, in the descending flow of saturated air, which partially impede the same and hinder the access of water-vapor to said surface, substantially as and for the purpose described.

7. In a lithographic press, the combination of the impression cylinder, the stationary inking-rolls at one side of the same, the reciprocating bed or printing-surface, and two damping mechanisms, *d*, located on opposite sides of the cylinder and inking mechanism, and each adapted, as described, to dampen the surface during its passage in both directions thereunder, whereby the damping of the stone is divided into four distinct operations, and thus the overdamping of the surface at any one time prevented.

JOHN W. OSBORNE.
